CLAIM

The ornamental design for a charging box, as shown and described.

DESCRIPTION

FIG. 1 is a front view of a charging box showing our new design, showing the cover opened;

FIG. 2 is a back view thereof;

FIG. 3 is a left-side view thereof;

FIG. 4 is a right-side view thereof;

FIG. 5 is a top view thereof;

FIG. 6 is a bottom view thereof;

FIG. 7 is a first perspective view thereof;

FIG. 8 is a second perspective view thereof;

FIG. 9 is a third perspective view thereof;

FIG. 10 is a fourth perspective view thereof;

FIG. 11 is a fifth perspective view thereof;

FIG. 12 is a sixth perspective view thereof;

FIG. 13 is a seventh perspective view thereof;

FIG. 14 is a front view of the charging box, showing the cover closed;

FIG. 15 is a back view thereof;

FIG. 16 is a left-side view thereof;

FIG. 17 is a right-side view thereof;

FIG. 18 is a top view thereof;

FIG. 19 is a bottom view thereof;

FIG. 20 is a first perspective view thereof; and,

FIG. 21 is a second perspective view thereof.

The broken lines in FIGS. 1, 7-10, 12 and 13 illustrate portions of the charging box that form no part of the claimed design.

1 Claim, 21 Drawing Sheets
